UNITED STATES PATENT OFFICE.

CHARLES H. MANN, OF DELTA, OHIO.

REVOLVER.

No. 907,069.

Specification of Letters Patent.

Patented Dec. 15, 1908.

Application filed May 23, 1907. Serial No. 375,285.

To all whom it may concern:

Be it known that I, CHARLES H. MANN, a citizen of the United States, residing at Delta, in the county of Fulton and State of Ohio, have invented new and useful Improvements in Revolvers, of which the following is a specification.

My invention relates to improvements in fire arms, particularly with reference to lock devices for the hammer to prevent accidental discharge of the fire arm, and also with reference to means for cocking the hammer, my said improvements being particularly adapted for use in revolvers but also adapted for use in other fire arms, and the said invention consists in the construction, combination and arrangement of devices hereinafter described and claimed.

In the accompanying drawings, Figure 1 is partly an elevation and partly a longitudinal sectional view of a revolver of the hammerless type provided with my improved locking and cocking devices. Fig. 2 is a similar view of a revolver of the hammer type provided with my improved locking and cocking devices.

The hammer 1 of the fire arm, which is here shown as provided with a pin 2 but which may be of any suitable construction, is provided in its lower edge, which is semi-circular and concentric with its pivot 3, with notches 4—5 providing shoulders 6—7. The usual spring 8 which is fastened at one end, as at 9, in the stock, has its free end engaged 35 with a notch 10 in the rear side of the hammer near its lower end. In the front side of the said hammer, at a point about opposite the notch 10, is a notch 11.

My improved locking device 12 for the hammer is in the form of a bell crank providing arms 13—14. Said arm 13 which extends forwardly in the stock under the hammer, is provided, on its upper side near its front end, with a shoulder 15 to engage the notches 4—5 and bear against either of the shoulders 6—7. The pivot of the hammer locking device is indicated at 16. The arm 14 is provided at its lower end with a forwardly extending finger piece 17 which operates in and extends from the front side of an opening 18 in the front wall of the hollow handle portion of the stock. A spring 19, which is here shown as substantially U-shaped, has one of its arms secured 50 in the stock and its other arm bearing under the front end of the arm 13 of the hammer

locking device and serves to keep the shoulder 15 of such arm 13 in engagement with either the notch 4 or the notch 5 of the hammer to keep the latter in half cock or full 60 cock position as may be required.

The hammer cocking mechanism comprises what I will term a trigger 20 and a link 21. Such trigger 20 is substantially in the form of a trigger and is provided at its upper end 65 with an arm 22 which forms an extension thereof and is pivotally mounted in the slot in the lower side of the stock, as at 23. The link 21 is pivotally connected at its lower end, as at 24, to the trigger. Said link extends upwardly and rearwardly from the trigger and is provided on its rear side, near its upper end with a rearwardly extending shoulder 25 which engages the notch 11 in the front side of the hammer. A spring 26, 75 the lower front end of which bears on and is secured to the upper side of the arm 22 of the trigger, bears at its rear upper end against the front upper portion of the link 21 to keep the shoulder 25 thereof in engagement with the notch 11 of the hammer.

The operation of my invention is as follows: In order to cock the fire arm, the trigger 20 is turned rearwardly and upwardly, which may be done by the pressure of a 85 finger against such trigger, thus causing the link 21 to move upwardly and turn the hammer therewith. The spring 19 serves to engage the shoulder 15 of the locking device 12 with the notch 5 or the notch 4 according to 90 whether the hammer is set at half cock or at full cock. Assuming the hammer to have been set at full cock, the same may be released to discharge the fire arm by pressing a finger against the finger piece 17 to cause 95 the shoulder 15 of the locking device 12 to disengage the notch 4 and the shoulder 6 of the hammer, as will be understood. It will be observed that the shoulder 15 of the locking device by engagement with the shoulder 100 of the hammer prevents movement of the latter in either direction until after said locking device has been pressed to disengage said shoulder 15 from its hammer.

Having thus described the invention, what 105 I claim as new and desire to secure by Letters Patent is:—

In a fire arm having a hollow stock, the combination of a hammer having cocking notches and also having a front notch, a 110 spring to actuate the hammer when the latter is released, a locking device for the ham-

mer comprising a bell-crank having a horizontal arm extending from the stock, and a vertical arm, said horizontal arm extending under the hammer and having a shoulder on its upper side and said vertical arm having a forwardly extending finger piece protruding from the stock, a spring acting on said bell crank to normally engage the shoulder of the horizontal arm thereof with one of the cocking notches of the hammer, and a cocking mechanism for the hammer

comprising a pivotally mounted trigger and a spring-pressed link pivotally connected to the trigger and having a shoulder engaged with the front notch of the hammer. 15

In testimony whereof, I affix my signature in presence of two witnesses.

CHARLES H. MANN.
